E. E. CHILDS

DANCING FIGURE TOY

Filed Feb. 14, 1925

Patented June 29, 1926.

UNITED STATES PATENT OFFICE.

EDWARD EARLE CHILDS, OF OAKLAND, CALIFORNIA.

DANCING FIGURE TOY.

Application filed February 14, 1925. Serial No. 9,136.

My invention is an animated toy of the dancing type and is intended to simulate a shuffle dance or shuffle and clog. I provide a manikin with somewhat loose jointed arms and legs and a loosely attached foot which when supported with the feet touching a vibrating board or base simulates the loose jointed shuffle and clog dance typical of negro dancers. A feature of my invention is that the manikin may be supported on the end of a horizontal stick, that the feet will touch a board or platen which may be vibrated by the hand or some implement. I provide a platen relatively thin at the end to be clamped to a table so that it will vibrate for some considerable time after a vibration is started.

I make the platen wide and thick at its outer end so that when the inner end is clamped tight to a table it will vibrate with a somewhat slow natural period of vibration. The platen may be periodically struck with the fist or a drum stick thereby maintaining its vibration. The feature of holding the manikin on the end of a stick held in the hand gives an irregularity to the dance which further simulates a shuffle dance.

The joints are so made that the arms, legs and feet will swing to a certain extent and abruptly stop to prevent a back jointed action. By various positions and arrangements of clamping the platen it may be vibrated in tune with music thereby making the manikin more or less keep time in step with the tune.

My invention will be more clearly understood from the following specification and drawings in which:

Figure 1 is a side view of the manikin, illustrating the stick for holding the body or trunk and supporting the manikin and the vibrating platen.

Figure 2 is a section of Figure 1 on the line 2-2 showing part of the upper, and lower leg and foot.

Figure 3 is a detail showing one of many upper leg, lower leg and foot actions.

Figure 4 is a detail showing another of many lower leg and foot actions.

Figure 5 is a section of the platen of Figure 6 on the line 5-5, with the length on a reduced scale and the thickness shown exaggerated.

Figure 6 is a plan view of the platen il-

lustrating a shape well suited to periodic vibration.

In the description anatomical and mechanical terms are used to simplify the specification. The trunk 1 may be any desired shape and have a fixed or loose adjustable head 2 and arms 3 pivotally connected to the shoulders 4. The upper arm 5 is connected to the lower arm 6 by a link 7 and may have the hand 8 connected to the lower arm by a link or with a rigid wrist 9 as shown. The upper and lower arms have a curve at the front 10 and 11 so they may bend forward but have squared back corners 12 and 13 to prevent a back jointed bend.

The legs 14 are pivoted to the side of the hip on a pin 15 and the upper leg 16 is connected to the lower leg 17 by a link 18, operating in slots 19 and held by rivets 20. The lower leg has an extension or ankle 21 to which the foot 22 is connected by link 23, operating in the close slot 24 in ankle by the pivotal rivet 25. The foot has a wide slot 26 and an aperture 27 in the link 28 slightly larger than necessary for the pin 28, thus allowing the foot to wobble slightly sidewise. The slot 26 in the foot also extends to the front and back of the pin 28 to allow the foot to cant to the front with the toe down or the reverse.

The links and slots at the joints allow a great many movements to be executed of which two are illustrated in Figures 3 and 4. It will be noted that the rounded corners 29 and 30 allow the lower leg to bend back, in a natural way, but that the angular corners 31 and 32 on the front of the leg prevent a back jointed action and bring the swinging leg to an abrupt stop on a forward swing. The ankle extension 21 allows the foot to swivel through 180 degrees as shown in Figures 3 and 4; and it may also swing on the pin 28.

The manikin is supported by a stick 33, preferably glued in a socket 34 in the trunk, so that the feet rest on a vibrating platen 35. This may be constructed a variety of shapes but should be of such shape and material that it will vibrate readily. I find a suitable platen may be made of wood, with a relatively wide outer end 36, a narrow inner end 37 adapted to be clamped to a table as indicated at 38 and with a spindled mid portion 39. It is desirable that the ends be 110

wider than the mid section as shown exaggerated in Figure 6.

The manner of use and action of the manikin is somewhat as follows:—The stick 33 is held in the hand so that the feet rest on the platen when it is still or in its center position of vibration. The platen is vibrated by being struck by the fist or a drum stick, either by the person holding the stick or someone else. The toe, being heavier than the heel, cant down and is struck by the vibrating platen and the force of the blow causes the legs to swing in an erratic way, with the heel, toe and flat foot striking the platen. A great measure of the comical effect is due to the hand not holding the manikin steady.

The manikin may be considerably modified, a stationary support and a mechanically vibrated platen may be used and the manikin dressed as desired, without departing from the spirit of my invention.

Having described my invention what I claim is:—

1. A dancing toy comprising a manikin having a trunk portion, an upper leg piv-

oted to the trunk portion, a lower leg connected to the upper leg by a link and pins, a foot connected to the lower leg by a link and pins, said foot being provided with an enlarged socket adapted to allow the foot to rotate in a vertical plane and to wobble sideways, and a jointed arm member pivoted to said trunk member.

2. In a dancing toy, the combination with a vibrating platform having a thin fixed end and relatively thick vibrating end of a figure consisting of a trunk member, an upper leg member pivoted to said trunk member, a lower leg member connected to said upper leg member by a link and pins, said leg members being provided with abutting faces adapted to engage each other when the leg members are in alinement, a foot member connected to said lower leg member by a link and pins, said foot member being provided with an enlarged socket to allow it to wobble laterally, a jointed arm member pivoted to said trunk member and a handle rigidly connected to the trunk member.

In testimony whereof I affix my signature.

EDWARD EARLE CHILDS.
